UNITED STATES PATENT OFFICE.

MAURICE ALLAND, OF ATLANTIC CITY, NEW JERSEY.

SHAVING BRUSH.

Application filed June 16, 1927. Serial No. 199,158.

The object of the invention is to provide improvements in shaving brushes broadly, and more particularly to combine with such brushes a stick of shaving soap.

5 Another object is to provide a substantially cylindrical shield carried slidably by the handle of the device and adapted when in one position to cover the brush, and in its opposite position to surround the said 10 handle and expose the brush for use.

Still another object is to provide a holder for a soap-stick, said holder normally closing the end of the handle opposite to the brush and removably supporting the soap- 15 stick in the former, said holder upon being disengaged from said handle serving to remove the soap therefrom and support the stick in such manner as to make it readily available for use for soaping and preparing 20 the face of a person for shaving.

A further object is to provide the holder with an aperture, and with an axially flexible disc longitudinally movable within said holder, and against which the soap- 25 stick normally rests in one extreme position, whereby pressure exerted axially upon said disc through said aperture both flexes and moves said disc longitudinally, with the result that the stub of unused soap 30 is adapted to be ejected therefrom.

And a still further object is to provide an improved means for assembling the ejecting disc with the soap-supporting member, said member being provided internally with a circumferential groove of larger diameter than 35 that of the opening into said member, so that the disc of larger diameter than said opening is axially flexed in order for it to pass through said opening, after which it snaps 40 into a substantially plane state within said receiving groove.

With these and other objects in mind, the present invention comprises further details of construction and operation fully brought 45 out in the following description, when read in conjunction with the accompanying drawings, in which Fig. 1 is a plan view of one embodiment of the invention with the soap and brush in threaded inoperative positions and protected respectively by the surrounding handle and brush-protecting cylinders; Fig. 2 is a longitudinal diametrical section of the same; Fig. 3 is a top plan view of the same; Fig. 4 is a view showing the handle 50 and brush in elevation while the former is shown as being surrounded by the brush-

protecting cylinder in cross-section and in withdrawn position; Fig. 5 is an elevational view of the soap-stick and holder therefor per se; and Fig. 6 is an enlarged diametrical 60 section through the soap holder and showing the manner of ejecting a stub of soap therefrom.

Referring to the drawings, there is a hollow cylindrical handle member 1, the same 65 at one end being provided with internal threads 2, and external radially aligned threads 3. The other end of said member is provided with internal threads 4 and radially outwardly thereof with a suitably 70 knurled raised surface 5, on the inner side of which the exterior of said member is provided for a short distance with external threads 6.

Referring particularly to Figs. 2, 3 and 6, 75 there is shown a holder for a soap-stick 7, said holder providing a cylindrical member 8, provided at its open end with external threads 9, adapted to normally engage the internal threads of the member 1, and said 80 member 8 being provided at its other end with a radially inwardly directed substantially plane flange 10, having a central aperture 11. The inner surface 12 of said member 8 is provided at its innermost extent ad- 85 jacent to the flange 10 with a radially larger circumferentially extending groove 13, in which is positioned an axially flexible nor- 90 mally plane disc 14 which is sprung into said groove by forcing the disc through the open 95 end of the said soap-supporting member.

Normally, the stick of soap 7 is inserted within the cylindrical surface 12 of the member 8 firmly against the disc 14 in its straight or plane position shown in Fig. 2, after which the holder 8 is adapted to be gripped manually for the purpose of applying the soap-stick to the face of a person about to shave, or for the purpose of securing the soap-stick within the member 1 upon suitable relative rotation in order to interengage the threads 9 and 4 of the respective mem- 100 bers.

In the otherwise open end of the handle member 1 there is removably secured an externally threaded means 15 which constitutes a support for the fixed ends of bristles which extend freely therefrom and constitute a brush 16. This brush when not in use may be surrounded and protected by a hollow 105 cylindrical member 17, which is open at its free end 18, but at its opposite end is pro- 110

vided with internal threads 19 which engage either the threads 3 of the handle member 1 when the device is not in use, or engage the threads 6 of said handle member as shown in Fig. 4 when the brush is in use and is duly exposed.

After long use of the soap-stick 7 and it has worn down to substantially the same depth as the supporting member 8, this remaining stub 7^a may be readily ejected by merely pressing manually with a thumb or finger through the aperture 11 directly upon and in contact with the central portion of the disc 14 which is capable of being flexed 15 into the curved shape shown in Fig. 6 and then moved the full longitudinal extent of the groove 13, with the result that the stub 7^a is forced from its holder and the latter is thereupon adapted to receive a fresh soap- 20 stick of normal length.

Having thus described my invention, what I claim and desire to protect by Letters Patent of the United States is:—

1. A brush, comprising a hollow handle, a 25 removable closure for one end of said handle having an aperture and adapted to support a soap stick, a flexible disc secured in

said closure and when manually flexed by pressure through said aperture being operative to eject said stick.

2. A brush, comprising a hollow handle, a removable closure for one end of said handle having an aperture and adapted to slidably receive and frictionally retain a soap stick, a radially enlarged circumferential groove within said closure, and an axially flexible disc secured and longitudinally movable within said groove, whereby manual engagement of said disc through said aperture flexes said disc and moves the same axially to eject a soap stick from within said closure.

3. A brush, comprising a hollow handle, a removable closure for one end of said handle having a centrally positioned aperture and adapted to slidably receive and frictionally retain a soap stick, a circumferentially extending groove within said closure and of greater diametrical measurement than the open end of said closure, and a disc of larger diameter than said groove and positioned in said groove.

In testimony whereof I have affixed my signature,

MAURICE ALLAND.
